UNITED STATES PATENT OFFICE

111,233

DESIGN FOR A SUCTION EVACUATOR FOR SURGICAL AND SIMILAR OPERATIONS

Scott M. Abbott, Chicago, Ill., assignor to The
Burrows Company, Chicago, Ill., a corporation
of Illinois

Application July 1, 1938, Serial No. 78,217

Term of patent 14 years

To all whom it may concern:

Be it known that I, Scott M. Abbott, a citizen of the United States and a resident of Chicago, county of Cook and State of Illinois, have invented a new, original, and ornamental Design for a Suction Evacuator for Surgical and Similar Operations, of which the following is a specification, reference being had to the accompanying drawing, forming a part thereof, in which the figure is a perspective view of a suction evacuator for surgical and similar operations, showing my new design.

The dominant features of my design reside in the portions shown in full lines in the drawing. The other side of the article is substantially like that side shown in the drawing.

I claim:

The ornamental design for a suction evacuator for surgical and similar operations, substantially as shown and described.

SCOTT M. ABBOTT.
